Patented Jan. 30, 1900.

J. S. REYNOLDS.
WINDOW FRAME AND SASH.

(Application filed Apr. 27, 1899.)

(No Model.)

UNITED STATES PATENT OFFICE.

JAMES S. REYNOLDS, OF MINNEAPOLIS, MINNESOTA.

WINDOW FRAME AND SASH.

SPECIFICATION forming part of Letters Patent No. 642,369, dated January 30, 1900.

Application filed April 27, 1899. Serial No. 714,710. (No model.)

To all whom it may concern:

Be it known that I, JAMES S. REYNOLDS, a citizen of the United States, residing at Minneapolis, in the county of Hennepin and State 5 of Minnesota, have invented certain new and useful Improvements in Window Frames and Sash; and I do declare the following to be a full, clear, and exact description of the invention, such as will enable others skilled in the art to which it appertains to make and use 10 the same, reference being had to the accompanying drawings, and to the figures of reference marked thereon, which form a part of this specification.

15 This invention relates to window frames and sash of a fireproof nature; and the object thereof is to provide devices of the character specified composed entirely of metal struck up from separate pieces securely connected 20 and forming, when properly assembled, a frame, including weight-boxes, inner and outer stops, with runways between them, a sill connection, and other necessary incidental features, and a sash having its parts also 25 formed exclusively of metal and including the rabbets for holding the edges of the glass lights and serving as receptive means for putty or other plastic material secured in the usual manner.

30 The invention consists of the construction and arrangement of parts, which will be more fully hereinafter described and claimed.

In the accompanying drawings, Figure 1 is 35 a perspective sectional view of a part of a frame and sash embodying features of the invention. Figs. 2, 3, and 4 are separate parts of a transverse vertical sectional view through the window frame and sash and indicating the arrangement at different points and with 40 in the same scale. Fig. 5 is a detail perspective view of a portion of one of the sash-corners, showing the manner of providing the sash-cord-fastening socket therein. Fig. 6 is 45 a horizontal sectional view showing the mode of forming the divisions or mullions between the glass lights in sash where such are employed and wherein also smaller lights or panes are utilized. Fig. 7 is a horizontal sectional view through one of the jambs of the 50 window-frame below the pulleys.

Like characters of reference are employed

to indicate corresponding parts in the several figures.

Referring now more particularly to the construction of the frame, the numeral 1 designates the jambs or pulley-stiles, and 2 the head-jamb. Both jambs 1 and 2 are to be formed of sheet-iron, steel, galvanized iron, or copper, as may be found necessary for different purposes, and of such weight or thickness as the applicant may demand. The pulley-stile 1 has outwardly-extending side flanges 3 and is entirely open at the back to form a weight-box 4, adapted to be closed at the rear by a wood filling 5, as clearly shown 60 by Fig. 7. The head-jamb 2 is constructed similar to the pulley-stile in each instance, and the opposite ends of the said head-jamb and pulley-strokes are connected through the medium of flanges on said pulley-strokes and bolts 65 passed therethrough and through an over-projecting portion of said jamb. The opposite ends of said head-jamb also extend out flush with the rear terminations of the flanges 3 and provide a top covering for the weight-boxes 4. 70 The only wood that will be used, if at all, aside from the filling 5 and a similar filling in the head-jamb 2, are facings or moldings 7 and 8, secured by machine-screws 9 and 10, passed through the said metal of the pulley-strokes and head-jams, and also by means of 75 wood-screws 11, inserted in the molding 7, and filling 5 of the weight-box. These facings or moldings can, however, be readily dispensed with and other metallic ornamentations or embossings substituted therefor and affixed to the similar exposed portions of the frame or be formed therein. A sill 12, also of box-like 80 form, is employed and has outer and inner end flanges 13, and, as shown in Fig. 4, is disposed 85 at an angle, but may be perfectly horizontal or constructed with the usual drops, all of which is obvious to those skilled in the art. To the inner portion of the sill the stool 14 is secured 90 by means of machine-screws 15, passing through a shouldered portion 16 thereof and the upper adjacent portion of the inner end of said sill. The upper part of each pulley-stile has a pair of pulley openings 17 formed 95 therein at a suitable distance apart and parallel, and in rear thereof pulley-brackets are 100 affixed, supporting pulleys 18, which are ex-

posed through the said openings. On the pulley-stiles 1, in a line centrally between the openings 17, parting-stops 19 are secured and consist of metal boxes of substantially U-shaped form, open at one side, and said open side in each instance being placed against the pulley-stile and the entire device secured in place by machine-screws 20, passed therethrough at regular intervals and the adjacent portions of said stile. The head-jamb is also supplied with a similar stop 21, which meets the upper ends of the stops 19 on opposite pulley-stiles, and thereby a complete divisional means is provided. The outside of the frame has fitted thereto an angle-iron 22, which, in a wood frame would be termed a "staff" bead or molding. This angle-iron extends entirely across the head-jamb 2 and over the outer parts of the pulley-stiles and is turned at the corners by the formation of cuts on a miter and forged and bent to form a solid corner, this operation being well understood and is not illustrated for this reason. One portion of the angle-iron projects inward and beyond the edge of the head-jamb and also the opposite edges of the pulley-stiles. By this means the outside stop is formed, and between the inner side of the parting-strip 19 and the adjacent edge of the molding 8 a runway for the inner sash is formed, and the runway for the outer sash is in like manner inserted between the outer edge of the said parting-strip and the projecting portion of the angle-iron 22.

35 As shown by Fig. 1, it is intended to dispense with the use of subjambs and the interior finish or moldings 7 and 8 applied directly to the frame, as set forth heretofore. When subjambs are required to be used, they 40 will be attached to the frame by first securing small angle-irons 22^a in place of the interior finish and fastened by machine-screws, and to these angle-irons the subjamb is connected, as shown in dotted lines by Fig. 7.

45 The metal of which the parts of the frame are made will be of sufficient thickness for tapping purposes, and the holes that are drilled or punched therein are each tapped to form secure threads to receive the machine-screws 50 connecting the several parts and particularly in the pulley-stiles, and thereby avoid the use of nuts or other auxiliary connecting devices. This mode of forming the tap-holes or openings is to accommodate the attachment of such 55 parts as are applied after the main part of the frame is set up and when the interior cannot be reached to apply auxiliary fastenings on the ends of the screws. These openings are located at proper intervals apart, as the several devices will be suitably gaged when manufactured for an afterfitting at the time of erection or placing in position of the frame. The sash 23 is also to be made exclusively of metal, the top rails and the side rails 27 and 60 28 respectively being in the form of sheet-metal boxes, as well as the bottom rails, which are mitered and riveted at the corners and in

dimensions of such size as to freely move within the runways formed on the pulley-stiles and heretofore referred to. The upper opposite corners of the sash are provided with sockets 29, which are open at the bottom, as at 30, and form means for attaching the weight-cords running over the pulleys 18. The upper end 31 of each socket 29 is open, and said 75 sockets thereby permit the sash to close up over the pulleys without obstruction. The top side rail or meeting-rails and bottom rail of each sash are composed of one piece of metal of any suitable nature and thickness, which 80 are turned and bent in the form shown, and the edges are brought together at the center of the inner rails, as at 32 and best seen in Figs. 2, 3, and 4. The one end of each portion of the sash, as stated, is turned over the 85 adjacent end and laps and confines the inner end of a sheet-metal rabbet 33, which is left unbent until the glass 34 is placed in position and then all around turned over the glass in angular contour to form a rabbet. 90 After the said rabbet has been thus arranged putty or other plastic material 35 is applied in the usual manner and is pressed in and around the said rabbet, and the glass is held in firm connection with the sash. It is preferred that the metal used in forming the rabbet be of copper or other soft metal cut to the proper width, having one edge turned to a right angle and inserted in the jointed edges of the stiles and top rail and the meeting-rail and bottom rail of each sash, which 95 provide a ridge or standing seam. After the angular-turned edge of the metal forming the rabbet is inserted in the parts of said standing seam and the latter then compressed 100 either by hammering and riveted where necessary or desirable the meeting-rails of the sash—viz., being the top rail of the bottom sash and the bottom rail of the top sash—are provided with the same form of ridge or standing seam as previously indicated, and in addition each has a lip or check 36, as clearly 105 shown by Fig. 3, continuous with the said rails and serving to close the intervening space between the sash and also provide a limit or 110 stop. Means for locking the sash closed can 115 be applied to these lips or checks 36.

As shown by Fig. 6, the mullions or divisions 37 between lights of glass are each to be formed of two pieces 38 of metal turned or 120 bent into box-like shape and the opposite edges extended out angularly on opposite sides to produce a ridge or standing seam to receive the rabbet for holding the glass, which is also of similar construction and arrangement. 125

The several parts of the sash are to be joined together and firmly riveted at each connection, the dependence for holding the different parts together being entirely on rivets. The several joints may be soldered, if 130 desired, for making a neat appearance; but said soldering does not serve as a means for fastening the joints and which is applied and used more as a filling.

As shown by Fig. 7, weights 39 move in the weight-box, being attached to the cord extending from the sash, as in the ordinary manner of window frame and sash construction.

5 While the preferred form of invention has been shown and descriptively disclosed, it will be understood that the proportions and dimensions might be varied as well as the contour to suit the application and also the minor details of construction without in the least departing from the nature or spirit of the invention or sacrificing any advantages thereof, and as long as the features of the 15 improved form of frame and sash are retained and including the disuse of wood or combustible material.

Having thus described the invention, what is claimed as new is—

- 20 1. A window-frame comprising a pulley-stile or jamb of hollow construction and forming a weight-box, and a staff-bead or angle-iron on the outer side to provide an outside stop for the sash.
- 25 2. In a window-frame, the combination of sheet-metal box-like pulley-strokes, head-jambs and sill, a staff-bead or angle-iron surrounding the outer portions of the pulley-strokes and head-jambs and partially projecting inward 30 to form an outside stop and a parting-stop also formed of metal and secured to the side stiles and head-jamb in proper relation to the inner projecting portion of the staff-head, and an inside stop.
- 35 3. In a window-frame, the combination of pulley-strokes and a head-jamb composed of sheet metal bent into box-like form and connected, and a box-like parting-stop also of

sheet metal secured in position by machine-screws inserted therethrough and through 40 tapped openings in the said stiles and jamb.

4. In a window-frame, the combination with metallic pulley-strokes, and metal stops of box-like shape secured thereto by machine-screws received in tapped openings in said 45 stiles.

5. In a window-frame, the combination of pulley-strokes of sheet metal bent into box-like form, a head-jamb and sill also of sheet metal and of box-like form, a connection between 50 the opposite ends of the head-jamb and the pulley-strokes, and a sash of sheet metal in the form shown with side and meeting rails of box form, provided with sockets at the upper opposite corners and bendable metallic glass- 55 securing devices embodying a rabbet, as set forth.

6. The combination with a metallic fire-proof window-frame of a sash having a frame composed of sheet metal and provided with 60 metallic means for holding the glass lights, the said sash being intermediately divided by mullions comprising opposite box-like sections with the edges formed into outwardly-projecting ridges or standing seams and holding soft sheet-metal strips to form rabbets 65 for the reception of the glass lights and over which putty or other plastic material is to be applied.

In testimony whereof I affix my signature 70 in presence of two witnesses.

JAMES S. REYNOLDS.
